UNITED STATES PATENT OFFICE.

FRANK L. WALTER, OF DAYTON, OHIO.

GAGE.

1,346,572.

Specification of Letters Patent. Patented July 13, 1920.

Application filed August 15, 1918. Serial No. 249,926.

To all whom it may concern:

Be it known that I, FRANK L. WALTER, a citizen of the United States, residing at Dayton, in the county of Montgomery and State of Ohio, have invented certain new and useful Improvements in Gages, of which the following is a specification, reference being had therein to the accompanying drawing.

This invention relates to gages, and more particularly to a work supporting structure for use in connection with an amplifying gage. In amplifying gages and the like, the work or article to be gaged is placed between a fixed work supporting device and a movable work engaging member, which work engaging member is so connected with an indicator that the movements of the work engaging member will be readable, in amplified form, on the indicator. The work or article which is to be gaged upon a device of this kind varies greatly in character, and work supporting devices of different kinds are necessary in order that the work may be properly supported with relation to the movable work engaging member. Moreover, the repeated contact of the work with the work supporting member, as the work is passed between the same and the work engaging member, tends to wear away the surface of the work supporting member and to form a depression or recess therein, which affects the accuracy of the reading on the indicator.

One object of the invention is to provide in an amplifying gage or the like a work supporting structure comprising a removable supporting member or base on which the work supporting devices proper are mounted, so that different bases may be provided for different work and may be interchangeably secured to the gage.

Another object of the invention is to provide means for adjustably mounting a work engaging member on the base so that when worn the member may be adjusted to bring a fresh or unworn portion of its surface into proper position with relation to the work engaging member of the gage.

It is also an object of the invention to provide a structure of this kind which will be very simple in its construction and which will be of such character that the parts

will be held firmly in their positions, but 55 can be readily loosened for adjustment or removal.

In the accompanying drawings Figure 1 is a perspective view of an amplifying gage showing one embodiment of my invention;

Fig. 2 is a sectional view of a portion of the structure shown in Fig. 1;

Fig. 3 is a front elevation of a slightly modified form of the invention; and 65

Fig. 4 is a side elevation of a portion of the device of Fig. 3.

In these drawings I have illustrated the invention as applied to an amplifying gage, corresponding in its main features of construction to the gage shown and described in the application for patent filed by me August 23, 1917, Serial No. 187,753, but it will be understood that the present embodiment of the invention has been selected for 70 the purpose of illustration only and that the invention may be applied to gages, or similar devices, of various kinds, and that the invention itself may take various forms.

The amplifying gage of the above mentioned application, in so far as it is necessary to illustrate the same in the present application, consists of a standard 1, having secured thereto a supporting bracket

2. Adjustably mounted on the standard 85 1, preferably by mounting the same in a split sleeve 3, is a shank 4 upon the upper end of which is mounted a cross arm or frame 5. Mounted in one end of this frame and arranged above the bracket 2 90 is a movable work engaging member or pin 6, which is connected with an indicator 7 in such a manner that the movements of the work engaging member will be transmitted to the needle of the indicator. The 95 connecting devices may be of any suitable construction, such as the lever arrangement shown in the above mentioned application.

The work supporting devices are carried by the bracket 2 and, in the above mentioned application, consist of a flat plate 100 rigidly secured to the bracket, but this plate can be used only with a limited class of articles to be gaged and, in order that work supporting devices of different kinds may be 105 mounted on the bracket 2, I have provided a removable base 8 which is adapted to carry the work supporting devices proper

and which may be constructed to accommodate the same to the particular work supporting device or devices with which it is to be used. Preferably, this base is in the 5 form of a plate adapted to rest upon a flat upper surface 18 of the bracket and to be rigidly secured thereto. As here shown, the flat face of the bracket is provided with a groove or channel 9 adapted to receive a rib 10 depending from the base plate and extending longitudinally thereof. The device 10 for attaching the base plate to the bracket, as shown in the present drawings, consists of a screw 11 extending vertically through 15 the bracket and into a screw-threaded socket formed in the base plate and, preferably, in the rib 10. In this manner, the base plate is readily removable and it will be obvious that any base plate comprising these broad 20 features of construction can be applied to the bracket.

In that form of the device shown in Figs. 1 and 2, the base plate is designed to support a work engaging member or anvil, upon 25 which the work rests while in contact with the work engaging member or pin 6. As has been explained, a work engaging member of this kind is subject to wear and it is desirable that it should be adjustable to 30 permit different portions of its supporting surface to be brought into proper relation to the work engaging member. The work supporting member or anvil, as shown at 12, in Figs. 1 and 2, is so mounted on the base plate that it can be quickly and easily 35 adjusted to different positions thereon, or entirely removed therefrom and a different member substituted therefor. In the construction here shown, the base plate is provided in its upper surface with a longitudinal 40 channel 13, in which the lower portion or base 14 of the anvil 12 is mounted, and in which it may be moved lengthwise. It will be understood, of course, that the anvil may 45 take any suitable form so long as the base fits properly within the channel 13. The work supporting member or anvil may be secured in adjusted positions on the base plate in any suitable manner, but I prefer 50 a clamping device which can be quickly and easily operated. In the present instance, the base plate is so constructed that the vertical side walls of the channel 13 constitute 55 clamping members which can be moved toward and from each other to clamp or release the anvil. To accomplish this, the lower surface of the base plate is so constructed that it will rest upon the supporting surface of the bracket 2 at its edges only, the 60 intermediate portion being cut away, as shown at 15, so that it will not contact with the surface of the bracket, and, when, as in the present instance, the base plate is provided with a rib 9, this rib is of such a depth 65 that it will not engage the bottom of its

groove when the base plate is in its normal position. With the base plate constructed in this manner, the attaching screw 11 acts as an operating device for the clamping jaws or side walls of the channel 13, it being 70 apparent that when the screw is inserted in the socket in the rib 9 and tightened down, the rib will be drawn downward toward the bracket and, inasmuch as the edges of the base plate are held against movement, the 75 upper edges of the side walls of the channel will be moved toward one another, thus bringing them into gripping engagement with the base of the anvil 12, the base plate having sufficient resiliency to permit it to 80 be thus distorted from its normal shape. To facilitate the clamping action of the jaws I have, in the present instance, provided the corners at the junction of the side walls with the bottom of the channel 13 with 85 grooves 16, as shown in Figs. 1 and 2.

It will be apparent that when it is desired to adjust the anvil it is only necessary to loosen the screw 11, without entirely withdrawing it from its socket, and after the 90 proper adjustment of the anvil has been made to again tighten the screw and thus cause the walls of the channel to grip the anvil. Such a construction enables the base plate to be used indefinitely, as it is subjected to very little wear. The work engaging member or anvil being a separable part of the structure, it not only can be adjusted as has been explained, but can be readily removed to enable another anvil to 95 be substituted therefor on the base plate.

In Figs. 3 and 4, I have shown a base plate 17 similar to the base plate 8 above described, but having means for carrying a different kind of work engaging device. 105 This base plate is provided at its inner or rear end with an enlarged head or cross arm 19, which fits into the space between the shank 4 and the base plate proper, and in the rear of the work engaging device. 110 This head, which preferably extends for some distance on each side of the base plate, has a bearing surface 20 arranged obliquely to the plane of the work engaging device, and is provided with a T-shaped slot 21. 115 This cross arm or head is adapted to carry a pair of tail stocks 22, which are adjustably secured thereto by means of bolts having their heads arranged in the slots 21, extending through the respective tail stocks 120 and provided with hand nuts 23 for clamping the same in position. Each tail stock is provided with a center pin 24 which is rotatably mounted therein and is, preferably, provided with a milled head 25 whereby it 125 may be rotated. The pins are, however, mounted in split bearings 26 which are provided with clamping screws 27, so that they may, if desired, be locked against rotation. 130 This type of work support is designed for 135

gaging cylindrical work such, for example, as a shaft, and serves not only to gage the size of the work, but also gage the same as to concentricity, because the center pins are caused to engage the centers at the ends of the work and as the latter is rotated any eccentricity thereof will be shown on the indicator.

The operation and manner of use of the invention will be understood from the foregoing description, and it will be apparent that I have provided a structure in which the base plate is readily interchangeable and in which the work supporting devices may be adjusted, either to bring different surfaces into operative relation with the work engaging device or to accommodate the same to work of different kinds or sizes. The device is very simple in its construction and is of a strong durable character, which not only is not liable to get out of order or to be broken, but which will always support the work supporting devices in proper relation to the work engaging device.

While I have shown and described one embodiment of the invention, I wish it to be understood that I do not desire to be limited to the details thereof, as obvious modifications will occur to a person skilled in the art.

Having now fully described my invention, what I claim as new and desire to be secured by Letters Patent, is:

1. In a gage, a working engaging member, a supporting structure having its upper surface arranged beneath and in a plane extending transversely to said working engaging member, a removable base formed separately from and rigidly secured to the upper surface of said supporting structure, a work supporting device, and means for attaching said work supporting device to said base.

2. In a gage, a working engaging member, a supporting structure having a supporting surface arranged beneath and in a plane extending transversely to said working engaging member, a removable base formed separately from and rigidly secured to said supporting surface, a work supporting device mounted on said base for adjustment relatively thereto and transversely to said working engaging member, and means for securing said work supporting device to said base in adjusted positions.

3. In a gage, a work-engaging member, a supporting structure having its supporting face arranged beneath and in a plane extending transversely to said work-engaging member and provided with a groove, a base plate supported on said face of said structure and having a projection extending into said groove, means for securing said base plate to said structure, and a work-supporting device carried by said base plate.

4. In a gage, a work-engaging member, a supporting structure having its supporting face arranged beneath and in a plane extending transversely to said work-engaging member and provided with a groove, a base plate supported on said face of said structure and having a projection extending into said groove, a work-supporting device mounted on said base plate for movement transversely to said work-engaging member, and means for securing said base plate to said structure and for securing said work-supporting device in adjusted positions on said base plate.

5. In a gage, a work-engaging member, a supporting structure having its supporting face arranged beneath and in a plane extending transversely to said work-engaging member, a base plate mounted on said face of said structure, a work-supporting device carried by said base plate, and means to detachably secure said base plate to said structure and to secure said work-supporting device in adjusted positions on said base plate.

6. In a gage, a supporting structure, a base plate separate from and mounted on said structure, a work supporting device carried by said base plate, and a device to secure said base plate to said structure and to secure said work supporting device in adjusted positions on said base plate.

7. In a gage, a supporting structure, a base plate carried by said structure, a work supporting device, and means carried by said base plate for clamping said work supporting device thereto.

8. In a gage, a supporting structure, a base plate carried by said structure, a work supporting device, means carried by said base plate for clamping said work supporting device thereto, and means for securing said base plate to said structure and for actuating said clamping means to cause the same to grip said work supporting device.

9. In a gage, a work-engaging member, a supporting structure, a base plate carried by said structure and having clamping members extending transversely to said work-engaging member and adapted to receive a work-supporting device, and means for causing said clamping device to grip said work-supporting member.

10. In a gage, a work-engaging member, a supporting structure, a base plate carried by said structure and having a channel therein extending transversely to said work-engaging member and adapted to receive a work-supporting device, and means for causing the side walls of said channel to move into clamping engagement with said work-supporting device.

11. In a gage, a supporting structure, a base plate carried thereby and having a longitudinal channel in the upper surface thereof, said channel being open at its ends

and means for distorting said base plate to cause the side walls of said channel to move one toward the other.

12. In a gage, a supporting structure, a base plate supported by said structure, said base plate being so shaped that it will engage said structure at its edges only, said base plate having a channel extending lengthwise thereof and between the lateral edges thereof, and adapted to receive a work supporting member, and means for depressing the intermediate portion of said base plate relatively to its edges to cause the side walls of said channel to grip said work supporting member.

13. In a gage, a supporting structure having a substantially flat upper surface, a base plate supported at its edges on said surface of said structure and having its intermediate portion normally out of engagement therewith, said base plate having in its upper surface a longitudinal channel arranged between the edges thereof and adapted to receive a work supporting member, and a screw extending through said supporting structure into said base plate to depress the intermediate portion thereof relatively to its edges and thus cause the side walls of said channel to move toward said work supporting member.

14. In a gage, a supporting structure having a groove in its supporting surface, a base plate supported at its edges on said structure and having a rib adapted to enter said groove, said rib and the intermediate portion of said base plate being normally out of engagement with those portions of said supporting structure lying directly beneath same, said base plate having in its

upper surface a longitudinal channel adapted to receive a work supporting member, and a screw extending through said supporting structure into the rib of said base plate and adapted to draw said rib downwardly relative to the lateral edges of said base plate.

15. In a gage, a base plate having a longitudinal channel in its upper surface between the lateral edges thereof and adapted to be supported at its edges only, whereby the intermediate portion of said base plate may be drawn downward relative to the edges thereof because the side walls of said channel to move one toward the other.

16. In a gage, a base plate having a longitudinal channel in the upper surface thereof to receive a work supporting member and having grooves formed therein at the corners of said channel, said base plate being adapted to be supported at its lateral edges only, whereby the intermediate portion thereof may be depressed to cause the side walls of said channel to move one toward the other.

17. In a gage, a work engaging member, a supporting structure, a base plate mounted on said supporting structure and having a longitudinal channel in one surface thereof, a work supporting anvil mounted in said channel for adjustment lengthwise thereof to various positions with relation to said work engaging member, and means for securing said anvil in adjusted positions in said base plate.

In testimony whereof, I affix my signature hereto.

FRANK L. WALTER.
